UNITED STATES PATENT OFFICE.

CHARLES L. WAGANDT, OF BALTIMORE, MARYLAND, ASSIGNOR OF ONE-HALF TO KEEN & HAGERTY, OF SAME PLACE.

SOLDERING-IRON.

SPECIFICATION forming part of Letters Patent No. 408,772, dated August 13, 1889.

Application filed June 11, 1889. Serial No. 313,864. (No model.)

To all whom it may concern:

Be it known that I, CHARLES L. WAGANDT, a citizen of the United States, residing in the city of Baltimore, in the State of Maryland, have 5 invented certain new and useful Improvements in Soldering-Tools; and I do declare the following to be a full, clear, and exact description of the invention, such as will enable others skilled in the art to which it appertains to 10 make and use the same.

My present invention relates to that class of soldering implements in which the tip or "iron" is heated by a flame of combustible gas, which is conveyed by suitable conduits 15 to and burns in contact with or in immediate proximity to such iron or tip. The tip is subject to comparatively rapid consumption from oxidation and wear, while the rest of the tool is practically permanent. The tip is therefore 20 made conveniently separable from its holder, the best and most economical means for this purpose being an external or male screw-thread upon the tip or iron and a corresponding internal or female thread within 25 the holder. It is also necessary, for the best results to provide means for the application of the heating flame or flames, the gas for which is delivered into the interior of the holder, to the exterior of the tip, and in such 30 manner that said flames shall have the maximum heating effect. To this end it has been the practice to form longitudinal channels or recesses upon the inner side of the holder, thereby removing portions of the screw- 35 thread above mentioned. By these channels the heating-flames issued at the sides of the iron; but I have found in practice that serious disadvantages accompany this construction. It is necessary to constantly restore the proper 40 shape of the tip by a forging operation, and whether this be performed upon the tip while it is in the holder or the tip be unscrewed and screwed tightly back after the forging, I have found that the screw-threads upon it, 45 being cut in a soft metal—copper—are cut, pressed out of shape, and partially destroyed by the sharp and hard edges of the channels formed, as above described, in the iron-holder transversely to its screw-threads. In my im- 50 proved soldering-tool this injury to the screw-

threads of the tip, by which its engagement by the holder is rendered very insecure, and which results in the loosening of the tip in the holder while in use, is entirely obviated. According to my improvement the channels 55 are formed in the soft-metal tip, while the screw-threads of the iron-holder are left continuous and unbroken. I have also found that the heating-flames are in this manner so confined and conducted along and partially 60 within the surface of the tip, being nevertheless fully supplied with air and allowed to freely burn with perfect combustion of the gas, that a marked increase in the calorific effect of the same amount of gas is realized. 65

In order to make my invention more clearly understood, I have shown in the accompanying drawings a means for carrying the same into practical effect.

In said drawings, Figure 1 is a side view of 70 a soldering-tool embodying my invention. Fig. 2 is a transverse section on line 2 2, Fig. 1. Fig. 3 is a perspective view of the soldering-tip detached.

Referring to the drawings, A indicates the 75 handle of the tool, and B the tubular shank secured therein and carrying at its forward end the holder C. This latter receives the combustible gas through said shank, and is provided with apertures c to promote the 80 burning of the heating-flames. At its forward end the holder is provided with a female screw-thread c'.

D is the soldering tip or iron, formed of 85 copper and properly shaped for soldering purposes at its forward end, as shown at d.

d' are longitudinal channels V-shaped in cross-section and decreasing in depth as they advance toward the soldering-point. The heating-flames have their exit from the holder C 90 through these channels and between the periphery of the holder and the central solid portion D' of the tip D, and are conducted by the channels toward the soldering-point. It will be seen that the flames are thus in a manner confined, and the dissipation and waste of their heat prevented, while two faces d² are provided for each flame for what may be termed the "absorption" of its heat. 95

The male screw-thread d³ is formed upon 100

the exterior of the ribs D^2 , which are formed by and lie between the channels d' .

The mode of operation of my invention has been sufficiently set forth in the foregoing 5 description of its construction.

Having thus described my invention, what I claim is—

In a soldering-tool, the combination, with the holder having an internal and continuous screw-thread, as described, of the soldering-tip having the longitudinal channels upon 10

its exterior and a corresponding interrupted screw-thread upon its exterior between said channels, substantially as and for the purposes set forth.

In testimony whereof I affix my signature in the presence of two witnesses.

CHARLES L. WAGANDT.
